[57] CLAIM

The ornamental design for a bypassing door track, as shown and described.

DESCRIPTION

FIG. 1 is a fragmentary perspective view of a bypassing door track showing our new design;

FIG. 2 is an end elevational view thereof, the opposite end being the mirror image;

FIG. 3 is a fragmentary top plan view thereof;

FIG. 4 is an elevational view of the left side as seen in FIG. 1;

FIG. 5 is an elevational view of the right side as seen in FIG. 1;

FIG. 6 is a fragmentary perspective view of second embodiment of our design;

FIG. 7 is an end elevational view thereof, the opposite end being the mirror image;

FIG. 8 is a fragmentary top plan view thereof;

FIG. 9 is an elevational view of the left side as seen in FIG. 6; and,

FIG. 10 is an elevational view of the right side as seen in FIG. 6.
